Int. Cl. D7—02

U.S. Cl. D7—131

Published under the Second Trial Voluntary Protest Program on Feb. 10, 1976, as document No. B510,346

FIG. 1 is a perspective front view of a popcorn popper cover embodying my new design;

FIG. 2 is a top view thereof; and

FIG. 3 is a cross-sectional view in elevation taken on line 3—3 of FIG. 2.

This is a continuation of design application Ser. No. 280,327, filed Aug. 14, 1972, and now abandoned.

I claim:

The ornamental design for a popcorn popper cover, substantially as shown and described.
